UNITED STATES PATENT OFFICE.

DON D. MYERS, OF TOLEDO, OHIO, ASSIGNOR TO INDUSTRIAL RESEARCH CORPORATION, OF TOLEDO, OHIO, A CORPORATION OF DELAWARE.

INSIDE HOOD-LOCK.

1,361,169.

Specification of Letters Patent. Patented Dec. 7, 1920.

Application filed May 12, 1919. Serial No. 296,313.

To all whom it may concern:

Be it known that I, DON D. MYERS, a citizen of the United States, residing at Toledo, county of Lucas, and State of Ohio, have invented certain new and useful Improvements in Inside Hood-Locks; of which I declare the following to be a full, clear, and exact description.

This invention relates to improvements in latches or locks for automobile hoods.

One of the objects of the invention is the provision of means for resiliently holding the hood to the hood support in order to eliminate rattling while the automobile is in motion.

Another object is the provision of a lock which may be located inside of the hood thereby improving the appearance of the car by eliminating unsightly projections.

Another object is the provision of means in connection with a lock of this character which shall permit the operating handle or key to be removed, thereby preventing unauthorized persons from obtaining access to the interior of the hood.

A further object is the provision of mechanism in which the pivot points are so related that when the device is in locking position the moving parts are beyond dead center, and thus the spring is enabled to hold them in that position.

Still another object is the provision of means tending to move the hood inward rather than outward when, for any reason, there is relative motion between the hood and hood support.

Other objects, and objects relating to details of construction and economies of manufacture, will appear as I proceed with the description of that embodiment of the invention, which, for the purposes of the present application, I have illustrated in the accompanying drawing, in which:

Figure I is a fragmental, elevational view looking toward the hood from the inside thereof, and showing the lock in operative position.

Fig. II is a similar view showing the device in unlocked position, part of the casing being broken away in order to more clearly illustrate the construction.

Fig. III is a vertical cross-section taken substantially on the line III—III, Fig. I.

Fig. IV is a plan view.

Similar reference characters refer to like parts throughout the views.

In the drawing, a side rail of an automobile chassis is indicated at 10. This rail forms a support for the hood 11, which is shown as finished around the bottom by being rolled up over a rod or wire 12. To the lower surface of the rail 10, adjacent the inner edge thereof, is secured in any suitable manner a short pin 13, which is inclined upwardly in order to provide an upwardly and inwardly sloping under surface for engagement by the locking hook.

At that point in the hood chosen for the location of the lock, the hood is reinforced by means of a metal plate 14, the lower end of which is rolled outwardly and upwardly around the lower rolled edge of the hood, as shown clearly in Fig. III. The plate 14 serves also as a part of the casing for the lock. Near the upper end of the plate there is a reamed hole formed directly opposite a hole in the hood 11. In the assembly of the device, a bushing 15, provided with a bevel base to fit the reamed hole in the plate 14, is pushed through that hole and the hole in the hood and the outer end of the bushing is then bent over against the outer wall of the hood, thereby firmly attaching together the hood, plate and bushing. At the upper end of the plate 14 is an integral portion comprising part of the lock casing, having a wall 16 bent outwardly at right angles from one edge of the plate 14 and a wall 17 bent at right angles to the wall 16, and thus parallel to the plate 14.

The wall 17 contains a circular opening which is directly opposite to, and the same size as, the opening in the bushing 15. The bushing 15 and the opening in the wall 17 form bearings for a rock shaft 18, which preferably terminates flush with the outer face of the bushing 15, and is provided with a bore 19 having at least one flat side intended to receive the correspondingly shaped shank of an operating handle or key (not shown).

The rock shaft 18 protrudes through an elongated slot 20 in the upper end of a flat metal strip or bar 21 which, at its lower extremity, is shaped to form a hook 22. The lower end of the rod 21 also has an integral

bent out portion 23 to which is fixed the lower extremity of a coil spring 24 for a purpose hereinafter to appear. The rod 21 is capable of a sliding motion up and down, 5 in which it is guided by the slot 20 surrounding the rock shaft 18. It is also capable of a swinging motion upon the shaft 18, said motion being limited in one direction by the end wall 16 of the casing, and in the other 10 direction by the attaching portion of a guiding clip 25, which preferably is stamped out of the reinforcing plate 14. Throughout most of its length the rod 21 lies flat against the plate 14, being held in that position by the clip 25 and by a collar 26, which surrounds the rock shaft 18.

Between the collar 26 and the wall 17 of the casing a crank 27, formed of a sheet metal plate folded along one edge, is mounted upon the rock shaft 18. The latter has a flat portion 28 along one side extending from the rear end forward as far as the hook rod 21. The holes in the collar 26 and both portions of the crank 27 are similarly shaped so as to turn with the rock shaft. The shoulder 29, formed at the end of the flat portion 28, by abutting against the collar 26 prevents movement of the shaft to the left as viewed in Fig. III, while its 30 movement toward the right is prevented by a ring guard 30, which contacts with the wall 17 of the casing, the ends of the ring extending into holes in the shaft, shown at 31 in Fig. III, in order to hold it in place.

35 Near the outer end of the crank 27 a headed pin 32 extends through the two portions thereof, its dislocation being prevented by any suitable means, as for instance, a cotter pin 33. The pin 32 forms a pivotal mounting for an arcuate shaped link 34, the upper end of which extends between the two portions of the crank 27. The lower end of the link 34 has a perforation through which extends the upper end of the coil spring 24. The motion of the crank in the direction of the arrow in Fig. I is limited by an edge of the wall 17, against which the head of pin 32 abuts.

50 The operation of the device will now be described. It being assumed that the hood is down and locked in place, and that the driver of the machine desires to open the hood, he inserts a key or operating handle in the socket 19 and turns the rock shaft 18 in the direction opposite to that of the arrow in Fig. I. As soon as the pin has passed the dead center above the rock shaft, the tension of the spring 24 assists the motion during a small part of the rotation of the shaft, 55 or until the tension of the spring is relieved. Thereafter, further rotation of the shaft in the same direction positively lowers the link 34, and the bottom end thereof acts upon the spring 24, the coils of which are now closed, 60 tending to push it downwardly. This pres-

sure is conveyed by the spring to the lug 23 and thence to the hook rod 21, which accordingly slides downwardly, being guided in its motion by the sides of the slot 20 co-operating with the rock shaft. This disengages the hook 22 from the pin 13. Now, in order to throw the hook out from under the pin the operator continues the rotation of the shaft 18, thereby swinging the crank 27 and with it the link 34, to the left to the position illustrated in Fig. II. The connection between the two portions of the crank 27 bears against the edge of the link 34 during this latter movement, so that the link cannot merely swing on the pivot 32. From the lower end of the link this swinging motion is transmitted to the spring 24, which in turn swings the hook 21 and the motion is continued until the rod is stopped by the end wall 16 of the casing as shown in Fig. II. If two or more locks are employed, the others are operated in the same manner, and the hood may then be swung up on its hinge.

70 In locking the hood the reverse operation is of course followed, the first part of the rotation of the shaft having the effect of swinging the hook 22 under the pin 13, after which further rotation lifts the hook rod 21 until the hook 22 presses against the under face of the pin, and then still further rotation puts the spring 24 under tension. The greatest tension obviously occurs when the pivot 32 is directly above the shaft 18, or in dead center position. Provision is made however, for a slight further rotation until 90 the movement is stopped by the edge of the wall 17 of the casing as shown in Fig. I. With the pivot in that position the force of the spring 24 acts not only to hold the hook 22 into engagement with the pin 13, 100 but also to pull downwardly upon the pivot 32, and thus keep the mechanism in the locked position. As will be observed, the force holding the hook 22 in engagement with the pin 13 acts entirely through the 110 spring 24. Hence the hook and pin remain firmly in contact at all times, even though the relative positions of the hood and hood support change, as they will do more or less when the car is in motion. For this reason 115 there is no rattling of the lock.

I am aware that the particular embodiment of my invention above described, and illustrated in the accompanying drawing, is susceptible of considerable variation without departing from the spirit thereof, and therefore I desire to claim my invention broadly, as well as specifically, as indicated by the appended claims.

120 I claim as my invention:

1. In combination with the hood and hood support of an automobile, a pin secured to and extending inwardly from said hood support, a rock shaft mounted in said hood, a hook adapted to engage the under side of 130

said pin and mounted for swinging and vertical sliding movement upon said shaft, and means operable by the rock shaft for swinging the hook into position under said pin and thereafter for raising the hook until it presses firmly against the under surface of the pin.

2. In combination with the hood and hood support of an automobile, a pin secured to and extending inwardly from said hood support, a rock shaft mounted in said hood, a hook adapted to engage the under side of said pin and mounted for swinging and vertical sliding movement upon said shaft, and means including a resilient element operable by the rock shaft for swinging the hook into position under said pin and thereafter for raising the hook until it presses resiliently against the under surface of the pin.

3. In combination with the hood and hood support of an automobile, a pin secured to and extending inwardly from said hood support, a rock shaft mounted in said hood, a hook adapted to engage the under side of said pin and mounted for swinging and vertical sliding movement upon said shaft, means including a resilient element operable by the rock shaft for swinging the hook into position under said pin and thereafter for raising the hook until it presses resiliently against the under surface of the pin, said means being adapted, when the shaft is rocked in the opposite direction, first to relieve the resilient pressure, then to lower said hook and thereafter to swing said hook to one side of said pin.

4. In combination with the hood and hood support of an automobile, a pin secured to and extending inwardly from said hood support, a rock shaft mounted in said hood, a hook adapted to engage the under side of the pin and mounted for swinging and vertical sliding movement upon said shaft, a crank fixed to said shaft, a link having its upper end pivoted near the outer end of said crank and a coil spring attached at one end to the

lower end of said link and at the other end to the lower portion of said hook.

5. In combination with the hood and hood support of an automobile, a pin secured to and extending inwardly from said hood support, a rock shaft mounted in said hood, a hook adapted to engage the under side of said pin, and mounted for swinging and sliding movement upon said shaft, a crank fixed to said shaft, a link having its upper end pivoted near the outer end of said crank, a coil spring attached at one end to the lower end of said link, and at the other end to the lower portion of said hook, and a stop for limiting the movement of said crank after it has passed to a position slightly beyond upper dead center.

6. In combination with the hood and hood support of an automobile, means for locking said hood to the hood support, comprising a rock shaft mounted in the hood, one end thereof being visible from the outside of the hood, the remainder of said means being located within the hood, said rock shaft being provided with an opening within its outer end adapted to receive a removable operating handle.

7. In combination with the hood and hood support of an automobile, a pin secured to and extending inwardly from said hood support, a rock shaft mounted in said hood, a hook adapted to engage the under side of said pin mounted for swinging and sliding movement upon said shaft, a crank fixed to said shaft, an arcuate shaped link adapted to embrace said shaft and having one end pivoted to the outer end of said crank, a coil spring attached at one end to the opposite end of said link and at the other end to the lower portion of said hook, the line of centers of said pivotal connection and the point of attachment of said spring to the hook lying to one side of said rock shaft, when the parts are in locking position.

In testimony whereof, I affix my signature.
DON D. MYERS.
